(57) **CLAIM**

The ornamental design for an electric spin scrubber, as shown and described.

DESCRIPTION

FIG. 1 is a front perspective view of an electric spin scrubber, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged plan view of its top surface;

FIG. 8 is an enlarged plan view of its bottom surface;

FIG. 9 is a perspective view of its usage state;

FIG. 10 is a perspective view of its disassembled state;

FIG. 11 is an enlarged detail view of area 11 in FIG. 1; and, FIG. 12 is an enlarged detail view of area 12 in FIG. 2.

The broken lines in the drawings illustrate the portions of the electric spin scrubber, which form no part of the claimed design.

The dash-dot-dash broken lines encircling the enlarged views are for annotative purposes only and form no part of the claim thereof.
